M. L. TRIMMER

DUMPING BODY.

Filed Nov. 11. 1922

UNITED STATES PATENT OFFICE.

MOSES LEROY TRIMMER, OF CRAIG, MISSOURI.

DUMPING BODY.

Application filed November 11, 1922. Serial No. 600,287.

To all whom it may concern:

Be it known that I, MOSES L. TRIMMER, a citizen of the United States, residing at

Craig, in the county of Holt and State of 5 Missouri, have invented certain new and useful Improvements in Dumping Bodies, of which the following is a specification, reference being had to the accompanying drawings.

10 This invention relates to certain improvements in dumping bodies, and it is an object of the invention to provide a device of this general character embodying a tail gate, and wherein novel and improved means are 15 employed to cause the tail gate to assume automatically an open position upon tilting of the body.

Another object of the invention is to provide a novel and improved device of this 20 general character, wherein the body will be caused to dump or tilt upon shifting of the center of gravity of the body, together with means to effect the desired shifting movement.

25 The invention consists in the details of construction and in the combination and arrangement of the several parts of my improved dumping body whereby certain important advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

35 Figure 1 is a view in elevation of a body constructed in accordance with an embodiment of my invention and in a tilting or dumping position; and

40 Figure 2 is a view in perspective of a portion of the mechanism employed for imparting initial shifting movement of the body.

45 As disclosed in the accompanying drawings, F denotes the supporting frame of a vehicle with which is associated the wagon body B. The rear portion of the frame F, adjacent each side thereof, is provided with an upwardly disposed member 1, the top face of which is disposed on a rearward and 50 downward incline. Pivotedly engaged with

said member 1 is a link 2 which is also pivotally engaged with the body B at substantially the longitudinal center thereof.

The body B, at each side thereof, is provided with a depending lug 3, which upon rearward shifting of the body B, contacts with the member 1, said movement of the body being sufficient to shift the center of gravity of the body and the load carried thereby to cause said body to tilt or swing 65 downwardly to discharge the load carried thereby.

Interposed between and operatively engaged with each side portion of the body B and the frame F is a retractile member 4 70 placed under tension as the body B tilts or swings into dumping position, the resultant tension of said member being sufficient to return the body B to its normal position after the load has been discharged. 75

Carried by and underlying the forward portion of the body B is a cross member 5, which, when the body is in its normal or horizontal position, engages beneath a catch or hook member 6 arranged at each side of 80 the frame F and extending upwardly therefrom, whereby the body B is effectively held in its normal position. It is to be understood that the shifting movement to effect the dumping or tilting of the body B, is also 85 sufficient to release the cross member 5 from the catch or hook member 6.

Rotatably supported by the frame F at a point rearwardly of the cross member 5 is 90 a rock shaft 7 provided with an upstanding arm 8. This arm 8 is operatively engaged with a rigid link 9 also pivotally engaged with the cross member 5. By proper rocking movement of the shaft 7 the body B will be shifted rearwardly to effect the desired 95 tilting or dumping movement of the body B.

The shaft 7 is also provided with a depending rock arm 10 which is pivotally engaged with a forwardly directed rod 11. 100 The rod 11 is coupled, through the medium of the turn buckle 12, or the like, with a second rod 14. This rod 14 has its forward end portion pivotally engaged with a link 15 also pivotally connected with a bracket 105 16 carried by the frame F. As herein disclosed the link 15 is arcuate in form.

Also pivotally engaged with the bracket 16 is an upwardly directed foot lever 17. 110 The pivoted or lower end portion of the

lever 17 is provided with an upwardly disposed arm 18 herein disclosed as sigmoidal in form. The arm 18 and the central portion of the link 15 are operatively connected. 5 through the instrumentality of the rigid link 19.

With the body B in its normal or horizontal position and held by each of the catch or hook members 6, forward and downward 10 swinging movement imposed upon the lever 17, preferably by the foot, results in upward pull being imposed upon the link 15 effecting a forward movement of the coupled rods 14 and 11. This forward movement of the 15 rods 14 and 11 rocks the shaft 7 in a direction to cause the arm 18 to swing upwardly. This upward movement of the arm 8 results in a rearward swinging movement of the body B sufficient to release the cross 20 member 5 and to bring a lug 3 in contact with a member 1, whereupon the body B, by gravity, swings downwardly into dumping position as indicated in Figure 1 of the accompanying drawing.

25 After the body B has discharged its load, the tension of each of the retractile members 4 will cause the body B to return automatically to its horizontal position and move rearwardly sufficient to cause the cross 30 member 5 to have locking engagement with each of the catches or hook members 6. During this movement, the lever 17 will swing upwardly and rearwardly and the upper end portion of the arm 18 will be 35 operatively engaged with the holding dog 20. This dog 20 is provided with a tail extension 21 to facilitate its release from the arm 18 when it is desired to effect a tilting of the body B.

40 The rear portion of the body B has associated therewith a drop tail gate G which assumes a closed position when the body B is in its normal or horizontal position. When the body is tilted the gate G is caused 45 automatically to move to open position.

In the present embodiment of my invention, this automatic opening movement of the gate G is effected by a mechanism comprising a shaft 22 supported by and extending transversely of the body B and extending beyond the opposite sides thereof. Each 50 end portion of the shaft 22 is provided with an upwardly directed arm 23 which has pivotally engaged therewith a link 24, said link 24 being also pivotally engaged with a side portion of the gate G.

The shaft 22, adjacent each end, is also provided with a depending arm 25 with which is pivotally engaged a link 26 also 55 pivotally engaged with a member 1, the pivotal connection of the link 26 with the body being common to the pivotal connection between said body and a link 2.

60 When the body B is initially shifted rearwardly, the links 26, through the instrumen-

tality of the arms 25, will effect a rocking movement of the shaft 22, sufficient to cause the arms 23 to swing the arms 24 outwardly sufficient to swing the gate G into open position. As the body B tilts, the gate G will 70 be free to further move into open position. When the body B is returned to its normal position, the mechanism just described will cause the gate G automatically to operate to its closed position.

75 From the foregoing description it is though to be obvious that a dumping body constructed in accordance with my invention is particularly well adapted for use by reason of the convenience and facility with 80 which it may be assembled and operated, and it will also be obvious that my invention is susceptible of some change and modification without departing from the principles and spirit thereof and for this reason I do 85 not wish to be understood as limiting myself to the precise arrangement and formation of the several parts herein shown in carrying out my invention in practice except as hereinafter claimed.

90 What is claimed is:—

1. In combination with a frame, a body mounted thereon for sliding movement, a link pivotally connected with the body and the frame, means to impart tilting movement to the body upon shifting of the body in one direction, a tail gate for the body, a rock shaft carried by the body and provided with a rock arm, a link pivotally engaged with the rock arm and with the frame, the pivotal connection between said last named link and frame being common to the pivotal connection between the first named link and the frame, and an operative connection between the rock arm and gate 95 to cause said gate to move into open position upon shifting of the body in one direction. 100

2. In combination with a frame, a body mounted thereon for sliding movement, a link pivotally connected with the body and the frame, means to impart tilting movement to the body upon shifting of the body in one direction, a tail gate for the body, a rock shaft carried by the body and provided with a rock arm, a link pivotally engaged 110 with the rock arm and with the frame, the pivotal connection between said last named link and frame being common to the pivotal connection between the first named link and the frame, a second rock arm carried by the shaft, a link operatively connecting the second rock arm and the gate to cause the gate 115 to move into open position upon shifting movement of the body in one direction. 120

3. In combination with a frame, a body mounted thereon for sliding movement, a rock shaft carried by the frame, an operative connection between the rock shaft and body to impart sliding movement to the body and to cause tilting movement of said body upon 125 130

- rotation of the rock shaft in one direction, a rock arm carried by said shaft, an arm supported by the frame for swinging movement, a link having one end portion 50
 5 pivotally supported by the frame, a rod pivotally engaged with the opposite end portion of the link and pivotally engaged with the rock arm of the shaft, and a second link pivotally engaged with the arm and
 10 with the link at a point between the pivotal connections of said first link with the frame and with the rod.
4. In combination with a frame, a body mounted thereon for sliding movement, a rock shaft carried by the frame, an operative connection between the rock shaft and body to impart sliding movement to the body and to cause tilting movement of said body upon rotation of the rock shaft in one direction, a rock arm carried by said shaft, an arm supported by the frame for swinging movement, a link having one end portion pivotally supported by the frame, a rod pivotally engaged with the opposite end portion of the link and pivotally engaged with the rock arm of the shaft, a second link 65
 15 pivotally engaged with the arm and with the link at a point between the pivotal connection of said first link with the frame and with the rod, and a holding dog engageable with the arm when the body is in one position to lock the body against sliding and swinging movement.
5. In combination with a frame, a body mounted thereon for sliding movement, a rock shaft carried by the frame, an operative connection between the rock shaft and body to impart sliding movement to the body and to cause tilting movement of said body upon rotation of the rock shaft in one direction, a rock arm carried by said shaft, 70
 20 an arm supported by the frame for swinging movement, a link having one end portion pivotally supported by the frame, a rod pivotally engaged with the opposite end portion of the link and pivotally engaged with the rock arm of the shaft, a second link
 25 pivotally engaged with the arm and with the link at a point between the pivotal connections of said first link with the frame and with the rod, and a pedal for imparting swinging movement to the arm.
6. In combination with a frame, a body mounted thereon for sliding movement, a rock shaft carried by the frame, an operative connection between the rock shaft and body to impart sliding movement to the body and to cause tilting movement of said body upon rotation of the rock shaft in one direction, a rock arm carried by said shaft, 75
 30 an arm supported by the frame for swinging movement, a link having one end portion pivotally supported by the frame, a rod pivotally engaged with the opposite end portion of the link and pivotally engaged with the rock arm of the shaft, a second link
 35 pivotally engaged with the arm and with the link at a point between the pivotal connections of said first link with the frame and with the rod, and a holding dog engageable with the arm when the body is in one position to lock the body against sliding and swinging movement.
7. In combination with a frame, a body mounted thereon for sliding movement, a rock shaft carried by the frame, an operative connection between the rock shaft and body to impart sliding movement to the body and to cause tilting movement of said body upon rotation of the rock shaft in one direction, a rock arm carried by said shaft, 80
 40 an arm supported by the frame for swinging movement, a link having one end portion pivotally supported by the frame, a rod pivotally engaged with the opposite end portion of the link and pivotally engaged with the rock arm of the shaft, a second link
 45 pivotally engaged with the arm and with the link at a point between the pivotal connections of said first link with the frame and with the rod, and a holding dog engageable with the arm when the body is in one position to lock the body against sliding and swinging movement, said dog automatically engaging the arm upon movement of the body to its normal position.

In testimony whereof I hereunto affix my signature.

MOSES LEROY TRIMMER.
